UNITED STATES PATENT OFFICE.

FREDERICK L. SARGENT, OF BURLINGAME, CALIFORNIA.

TOWEL DISPENSER.

1,427,420.

Specification of Letters Patent. Patented Aug. 29, 1922.

Application filed November 7, 1921. Serial No. 513,381.

To all whom it may concern:

Be it known that I, FREDERICK L. SARGENT, a citizen of the United States, residing in Burlingame, county of San Mateo, 5 and State of California, have invented a new and useful Improvement in a Towel Dispenser, of which the following is a specification.

My invention relates to improvements in 10 dispensers for paper towels and the like wherein provision is made for dispensing towels from an oscillating container directly to a dispensing slot.

The primary object of my invention is to 15 provide an improved dispensing device for paper towels and the like.

Another object of my invention is to provide an improved container adapted to reduce the strain upon the towel during withdrawal.

A further object of my invention is to provide an improved device of the character described wherein an oscillating container is arranged to dispense a towel directly through a dispensing slot to facilitate the withdrawal of the towel and to insure the feeding of successive towels into dispensing position.

A further object is to provide an improved towel container adapted for removal from a separate casing to facilitate the introduction thereinto of fresh supplies of towels.

A still further object is to provide an improved device which will present a neat appearance and which may be manufactured and installed at a low cost.

I accomplish these and other objects by means of the device disclosed in the drawings forming a part of the present specification wherein like characters of reference are used to designate similar parts throughout said specification and drawings, and in which:

Fig. 1 is a transverse section showing the towel container in normal position.

Fig. 2 is a transverse section showing the manner in which the towel container is oscillated by the withdrawal of a towel to dispense said towel directly through the dispensing slot.

Fig. 3 is a vertical longitudinal section of my improved dispensing device.

Referring to the drawings the numeral 1 55 is used to designate in general a casing having a top 2 hingedly connected as at 3 and

provided with an arcuate bottom 4 having a longitudinally disposed dispensing slot 6 formed therein.

Bearing slots 7 are formed at the top 60 edges of the ends of the casing 1 in vertical alignment with the slot 6, to receive and removably engage bearing lugs 8 formed at the top edges of a towel container 9 arranged to be suspended by said bearing lugs 65 within the casing and adapted for oscillating movement therein.

The container 9 is adapted to receive a plurality of interfolded paper towels 11 or other similar material, said towels being 70 supported by inwardly turned edges 12 formed upon the sides of the container at the bottom edge thereof, said edges 12 extending inwardly sufficiently to engage the edges of the towels. The container is open 75 at both top and bottom and the ends are inclined at the top from the bearing lugs 8 to the sides of the container to permit oscillating movement thereof as shown in dotted lines in Figs. 1 and 2 of the drawings.

The casing 1 is arranged to be secured upon a wall or other supporting surface by means of extensions 14 having apertures 15 adapted to engage the heads of screws or other supporting elements, not shown. However, the manner of supporting my dispenser does not form a material part of my present invention. The forward side of the casing is preferably rearwardly inclined as 90 shown in the drawings in order to minimize the space between the container and the casing.

The top 2 is arranged to be secured in closed position by means of a hasp 16 or other suitable securing means. When the top is moved upon the hinge 3 into an open position the container may be filled directly or it may be removed from the casing and filled at some more convenient place, as 100 desired.

The operation of the device is as follows:

A supply of interfolded towels having been placed in the container, the container is placed in position within the casing 1 with 105 the free end 17 of the lowermost towel 11 extending outwardly in normal dispensing position through the slot 6. When it is desired to remove a towel, the end 17 is grasped and pulled away from the casing. 110 As the end 17 is moved through the slot 6 the weight of the towels within the con-

tainer resting upon the edges 12 will cause the container to be moved from the normal mid-position shown in full lines in Fig. 1 to the position shown in dotted lines, thereby bringing the folded portion of the towel supported upon the edge 12 directly above the slot 6. A slight downward pull will now disengage the folded edge of the towel from the edge 12 of the container and it may be moved directly through the slot. The edge of the succeeding towel interfolded within the first towel will be carried by said first towel through the slot and the towels remaining in the container will drop down and be supported by the edge 12 as before. The container will swing back from its displaced position thereby moving the towel through the slot and feeding the free end of the succeeding towel into normal dispensing position from which it may be withdrawn in the manner above described, the container being moved in the opposite direction to the position shown in dotted lines in Fig. 2 of the drawings. Successive withdrawals operate to oscillate the container above the slot 6 so that the folded edges supported upon the edges 12 are dispensed directly through the slot 6.

In my preferred construction illustrated in the drawings the bottom of the casing and the bottom of the container are both made arcuate in shape to describe circles drawn from the axis of the bearing lugs 8, only a slight clearance being allowed thereby insuring that the towels will not be crowded down out of engagement with the edges 12 of the container. The weight of the towels is carried upon the edges 12 of the container and as the container will move freely upon its pivot bearings it is assured that the towel may be removed with a minimum strain upon the towel.

The device as described may be easily made of sheet metal at a moderate cost, and the finished device may be decorated to conform to its surroundings.

Having thus described my invention what I claim as new and desire to secure by Letters Patent is:

50. 1. A paper towel dispenser comprising a casing having a dispensing slot in the bottom thereof; a towel container pivotally mounted within the casing and arranged to oscillate above said dispensing slot, said container being adapted to receive a plurality of interfolded towels, the free end of the lowermost towel normally extending outwardly through the slot; and means for supporting the towels within the container 55 to permit oscillating movement thereof when said towel is withdrawn through the slot.

65. 2. A paper towel dispenser comprising a casing having a dispensing slot in the bottom thereof; a towel container pivotally mount-

ed within the casing and arranged to receive a plurality of interfolded towels, the free end of the lowermost towel normally extending outwardly through said slot; and inwardly turned edges formed upon the sides 70 of the container at the bottom thereof to support the towels within the container to permit oscillating movement of the container when said lowermost towel is withdrawn through the slot whereby the lowermost towel and the interfolded end of the succeeding towel may be moved directly 75 from the container through said slot.

3. A paper towel dispenser comprising a casing provided with an arcuate bottom having a dispensing slot therein; a towel container pivotally mounted within the casing and arranged to receive a plurality of interfolded towels the free end of the lowermost towel normally extending outwardly 80 through said slot, said container being arranged to oscillate adjacent the arcuate bottom of the casing; and inwardly turned edges formed upon the sides of the container at the bottom thereof to support the towels 85 within the container to permit oscillating movement of the container when said lowermost towel is withdrawn through the slot whereby the lowermost towel and the interfolded end of the succeeding towel may be 90 dispensed directly from the container through the slot.

4. A paper towel dispenser comprising a casing having a dispensing slot formed in the bottom thereof and also having bearing 100 slots formed upon the upper edges of the ends thereof; a towel container adapted to receive a plurality of interfolded towels, said container being provided with bearing lugs upon the ends thereof to engage the 105 bearing slots in the casing whereby said container may be mounted for oscillating movement within the casing; means for supporting the towels within the container, the free end of the lowermost towel normally 110 extending through the dispensing slot to permit withdrawal thereof said withdrawal operating to oscillate the container to dispense the towel and the interfolded end of the succeeding towel directly through the 115 dispensing slot.

5. A paper towel dispenser comprising a casing having a dispensing slot in the bottom thereof; a towel container removably mounted within the casing; and adapted for 120 oscillating movement; and means formed integrally with the container for supporting a plurality of interfolded towels therein, the lowermost towel having its free end normally extended through the dispensing slot 125 to permit withdrawal through the slot, said withdrawal operating to oscillate the container to dispense the towel and the interfolded end of the succeeding towel directly through the slot.

6. A paper towel dispenser comprising a casing provided with a hingedly connected top and with an arcuate bottom, said bottom having a dispensing slot formed there-
5 in; a towel container removably mounted within the casing and adapted for oscillating movement therein; inwardly turned edges formed upon the sides of container at the bottom thereof to support a plurality of interfolded towels, the lowermost towel having its free end normally extended through the slot to permit withdrawal, said withdrawal operating to oscillate the container adjacent the arcuate bottom of the
10 casing to dispense the towel and the interfolded end of the succeeding towel directly through the dispensing slot.

7. A paper towel dispenser comprising a casing provided with a hingedly connected
15 top and an arcuate bottom, and having a dispensing slot formed in the bottom and bearing slots formed in the ends at the top; a towel container; bearing lugs formed upon the ends of the container to engage the bearing slots for removably mounting said container for oscillating movement within the casing; inwardly turned edges formed upon the sides of the container at the bottom thereof to support a plurality of interfolded towels, the lowermost towel having its free end normally extended through the dispensing slot to permit withdrawal therethrough, said withdrawal operating to oscillate the container adjacent the arcuate bottom of the casing to dispense the towel and the interfolded end of the succeeding towel directly through the dispensing slot.

In witness whereof I hereunto set my signature.

FREDERICK L. SARGENT.
